ARTICLE VENDING MACHINE

John L. Scott, P.O. Box 177, Ottawa, Ontario, Canada

Filed July 3, 1959, Ser. No. 824,891

4 Claims. (Cl. 221—116)

This invention relates to article vending machines, and more particularly to article delivery mechanism therefor.

In vending machines for relatively heavy articles such as large blocks of ice which may be of ten to twenty pounds or more in weight, it is necessary to provide a special delivery mechanism which is sufficiently strong and heavy in structure to adequately support the articles during the delivery step. As a result, vending machines for heavy articles such as blocks of ice are currently quite high in cost and, while the use of vending machines of this type is widespread, their cost justifies installation only in locations where heavy sales of articles are likely to occur.

It is an object of this invention to provide an article delivery mechanism for vending machines which is of simplified construction and reduced cost, which is capable of receiving an increased charge of articles to be vended, and which is subject to long, trouble-free, and position operation.

The invention will be described with reference to the accompanying drawings, in which

FIGURE 1 is a side elevation of a vending machine in accordance with the invention,

FIGURE 2 is a plan view of one portion of the article delivery mechanism,

FIGURE 3 is a plan view of another portion of the article delivery mechanism,

FIGURE 4 is a cross sectional view on line 4—4 of FIGURE 1, and

FIGURE 5 is a perspective view of an article engaging dog.

The apparatus illustrated will be described with particular reference to the vending of blocks of ice.

In the drawing, 1 is an insulated housing of conventional structure, having an opening 2 for delivery of articles and an external platform 3 to receive the delivered article. The opening 2 is provided with a closure 4 which may be of the flexible curtain type and which will flex outwardly on engagement by an article to permit passage of the article through the opening and will thereafter automatically return to the closed position.

Delivery mechanism in accordance with the invention comprises a pair of laterally aligned parallel conveyors 5 supported on the bottom wall of the housing by means of transverse members 6. Each conveyor 5 has a frame comprising longitudinal bars 7 and transverse bars 8 which may consist of lengths of angle iron as shown. Each conveyor comprises a pair of sprockets 9 having their shafts 10 freely journaled in bearing members 11, and an endless chain 12 mounted on the sprockets. Each chain has an upper substantially horizontal path of travel and a lower return path of travel also substantially horizontally disposed.

Each chain is supported during its upper path of travel on a pair of spaced metal strips 13 whereby each alternate horizontally disposed link of the chain rides on the edge portions of the two strips and each alternate vertically disposed link of the chain projects through the slot 14 formed between the strips and extends above and below the strips.

Each conveyor is provided with a pair of longitudinal ice carrying rails 15 one on each side of the chain. It will be apparent that each pair of rails is arranged to support a row of ice blocks 16 with the upper path of travel of the chain located directly below the overlying

2

row of ice blocks and substantially centrally of each row. Each conveyor has a rearward end 17 and a forward or discharge end 18.

Each row of ice blocks is connected to the underlying chain 12 by means of a removable dog 19 which comprises a plate 20 arranged to be seated upon the strips 13 and having a depending tooth 21 arranged to extend through a horizontal link of the chain for engagement thereby and an upright cleat 22 for engagement with the exposed end surface of the end block of the row of ice blocks adjacent the rearward end of the conveyor. It will be apparent that if movement is imparted to each of the chains 12 whereby the upper travelling path of travel thereof is in a direction moving from the rearward to the forward end of the conveyor, the blocks of ice will be successively discharged over the discharge ends of the chains.

Means for imparting successive increments of movement alternately to each chain in a direction to move the chain forwardly in its upper path, each such increment of movement being approximately equal to the length of an ice block, are provided. Such means comprises, for each conveyor, a pitman arm 23 pivoted to a crank arm 24. The crank arms 24 are fixed to a common shaft 25 journaled in bearings 26 mounted on frames 27. Shaft 25 is driven by means of sprockets 28, 29, chain 30, speed reducer 31, motor 32, and motor shaft 33.

The free end of each pitman arm 23 is provided with a tooth 34 which rides on the top of the upper travelling portion of a chain adjacent the rearward end thereof. Each tooth 34 is somewhat inclined, as shown in FIGURE 1 whereby on forward movement of the pitman arm it will fall into a horizontal link of the chain and engage the same to move the chain forwardly whereas on rearward movement of the pitman arm it will ride rearwardly over the chain links.

It will be apparent that a rearward section of the upper path of each chain is free of ice blocks to accommodate the stroke of the pitman arm on the chain. The length of stroke of each pitman arm is approximately equal to the length of a block of ice. Moreover, it will be observed that when one pitman is at the end of its forward stroke, the other pitman arm is at the end of its rearward stroke. Thus, on rotation of shaft 25, the pitman arms 23 will alternately move the chains 12 a distance approximately equal to the length of an ice block to discharge one block of ice alternately from the discharge end of each conveyor.

Means for guiding each pitman tooth 34 in its movement over a chain 12 comprises a pair of spaced strips 35 between which the tooth is located during its strokes.

Means for guiding the ice blocks discharged over the discharge ends of the chains through the opening 2 are provided and comprise slides 36 and 37 located at the discharge ends of the two conveyors. Each slide is preferably mounted on spring hinges 38 carried by a transverse frame member 39 closely adjacent the discharge ends of the conveyors. The hinges 38 normally hold the slides in an elevated position (as indicated in FIGURE 1) so that access to the interior of the housing through the opening 2 is avoided. However, on engagement by a block of ice, each slide is adapted to swing downwardly under the weight thereof. Each slide is in alignment with a conveyor 5, opening 2 being in alignment with slide 36. Thus, on engagement by a block of ice, slide 36 provides an inclined surface leading to opening 2 and the block of ice slides down such surface and through the opening onto the platform 3. Slide 37 is offset with respect to opening 2 and is provided with an inclined rail 40 which has an end portion 41 engaging the ice-receiving surface of adjacent slide 36. When an ice block engages slide

37 and swings it into downwardly inclined position, the portion 41 of the rail also swings slide 36 into downwardly inclined position. When the ice block engages rail 40 it is deflected laterally onto slide 36 and thence out of opening 2. Slide 37 may be provided with ribs 42 to facilitate sliding movement of ice thereon. An ice-retaining side rail 43 may be provided on slide 36.

Means are provided for maintaining each chain 12 in alignment during its return or lower path of travel and comprises a triangular frame 44 suspended from transverse bars 8 and preferably provided with a bearing rail 45, triangular in cross section as shown in FIGURE 4. Each rail 45 has a lowermost apex and side walls diverging upwardly therefrom to provide a triangular trough for reception of the chain. It will be apparent that the chain 12 will seat in rail 45 with its alternate links maintained in vertical and horizontal position by reason of the triangular configuration of the rail, as clearly shown in FIGURE 4.

Coin-actuated control mechanism for vending the blocks of ice one at a time is provided but is of conventional nature and forms no part of the present invention. Suitable mechanism is diagrammatically illustrated in the drawing and comprises a power line 46 connected to motor 32 through junction boxes 47 and 48 and arranged to supply power for driving the motor. A coin-actuated mechanism 49 is mounted on the housing adjacent opening 2 and has an electrical connection with the motor circuit through junction box 47, the arrangement being such that on insertion of an appropriate coin in the mechanism 49, the motor circuit will be energized to start the motor and eject one block of ice through opening 2. A switch 50 has an actuating arm 51 pivotally suspended therefrom. The arm 51 has a pair of fingers 52 vertically suspended from the arm and each located opposite one of the rows of ice block forwardly of the row and above a slide 36 or 37. Thus, when a block of ice slides down a respective slide, it will engage a finger 52 and swing it forwardly. As the ice block leaves the slide, the finger swings back into vertical position. This movement actuates the switch 50, which has an electrical connection 53 with the motor circuit via junction box 47, and opens the motor circuit to stop the motor.

A second switch 54 also has an actuating arm 51 with suspended fingers 52 which, however, are positioned directly above the rows of ice block, each finger engaging the top surface of the forward ice block of a respective row and being thereby swung forwardly in the position shown in FIGURE 1. As the last block of ice is ejected, the fingers 52 and arm 51 of switch 54 swing into vertical position and thus actuate the switch, which also has an electrical connection 55 with the motor circuit, to break the motor circuit. Thereafter, any coin inserted in the mechanism 49 will not start the motor but will be returned to the customer.

A main control switch 56 may be provided in the motor circuit.

Tension adjusting means for each chain 12 may be provided and as shown comprises a supporting frame 57 for one of sprockets 9 slidably mounted on frame members 58 and adjustable as to position thereon by means of screw-threaded rods 59.

I claim:

1. In a coin-controlled vending apparatus, article delivery mechanism comprising a pair of conveyors each having an endless chain, each said chain having a sub-

stantially horizontal upper path of travel, means supporting each said chain during said upper path of travel comprising a pair of longitudinally extending spaced strips, said chain having alternate links engaging said strips and disposed in a substantially horizontal position and alternate links extending between said strips and disposed in a substantially vertical position, stationary article supporting rails disposed above said upper path of travel and forming the sole means for supporting the articles, and an article engaging dog projecting above the rails and having a depending tooth freely insertable in any one of said horizontal links for selective positioning in said chain and travel therewith, said chains being arranged in laterally aligned relation, and means for moving each said chain alternately in successive increments of movement comprising a driven shaft, a pair of crank arms carried by said shaft and revolvably driven thereby, and a pitman arm freely swingably connected to each said crank arm and having a free end portion overlying and gravitationally urged toward one of said upper paths of travel, each said free end portion having a depending tooth engageable with one of said chains to move said chain in one direction, each said pitman having a forward and a rearward stroke.

2. Coin-controlled vending apparatus as defined in claim 1, including means for maintaining said link positions during the lower path of travel of said chain comprising a trough having diverging side walls, said horizontally disposed links engaging said side walls.

3. In an article delivery mechanism, an endless chain conveyor comprising an endless link chain having a substantially horizontal upper path of travel, means supporting said chain along said upper path of travel comprising a pair of longitudinally extending spaced parallel strips, said chain having alternate links slidably engaging said strips and disposed in a substantially horizontal position, the other links of said chain extending between said strips and disposed in a substantially vertical position, laterally spaced stationary article supporting rails disposed above the upper path of travel of said chain and forming the sole means for supporting the articles, and means supported on said strips and engaging the article above the rails and having a depending tooth freely insertable in any one of said horizontal links for selective connection to said chain at any point thereon and for travel therewith, and means for moving said chain in successive increments of movement.

4. The structure as defined in claim 3 wherein said article engaging means includes a body member having an upstanding abutment thereon for engaging the article, and outwardly extending flanges engaging the strips outwardly of the horizontal links whereby none of the weight of the article engaging means is supported by the chain.
